UNITED STATES PATENT OFFICE

2,572,312

CONDENSER ASSEMBLING MACHINE

James S. Burge and Don E. Key, Anderson, Ind.,
assignors to General Motors Corporation, Detroit, Mich., a corporation of Delaware

Application July 15, 1946, Serial No. 683,677

13 Claims. (Cl. 226—2)

1

This invention relates to the manufacture of electrical condensers, more particularly those comprising a winding of two foil strips and a plurality of paper strips insulating the foils from each other and having the margins of the two foils exposed, respectively, at the ends of the winding, a non-conducting tube surrounding the winding, a metal can enclosing the winding and tube, a conducting member contacting the bottom or closed end of the can and the adjacent foil margin, a conducting member contacting the other foil margin, a lead wire connected with the second conducting member, and a resilient, non-conducting washer surrounding the lead wire, the edge of the can adjacent its open end being crimped against the resilient washer which applies pressure to the second conducting member to force it against the adjacent foil margin and to force the winding toward the bottom of the can to squeeze the first conducting member between the bottom of the can to provide a good electrical connection between the foil margins and the lead wire and can, respectively.

An object of the invention is to provide a machine for assembling parts of the condenser and for crimping the can against the resilient washer permanently to secure the parts of the condenser.

A further object is to provide means for stopping the machine automatically in case parts are missing from an assembly or not properly located.

Further objects and advantages of the present invention will be apparent from the following description, reference being had to the accompanying drawings, wherein a preferred embodiment of the present invention is clearly shown.

In the drawings:

Fig. 1 is a perspective view of the machine taken in the direction of arrow 1 of Fig. 9.

Fig. 2 is a fragmentary perspective view in the direction of arrow 2 of Fig. 9, and shows the left end of the conveyor, dial and ram of the hydraulic press of the machine.

Fig. 3 is a fragmentary perspective view in the direction of arrow 3 of Fig. 9, and shows the winding checker, the winding feeder, the washer checker and washer feeder.

Fig. 4 is a fragmentary perspective view in the direction of arrow 4 of Fig. 9, showing the washer checker, washer feeder, tube checker and tube feeder.

Fig. 5 is a fragmentary perspective view in the direction of arrow 5 of Fig. 9, and shows the can checker and can feeder and a portion of the driving and control mechanisms.

Fig. 6 is a fragmentary perspective view in the direction of arrow 6 of Fig. 9, and shows the can feeder, can checker and tube feeder.

2

Fig. 7 is a fragmentary perspective view in the direction of arrow 7 of Fig. 1, and shows a portion of the machine driving mechanism.

Fig. 8 is a fragmentary perspective view in the direction of arrow 8 of Fig. 9, and shows cams for operating the various feeding and checking mechanisms and the gearing for operating the upper feeds of the can, tube and winding feeders.

Fig. 9 is a diagrammatic plan view of the machine.

Figs. 10 and 11 taken together, constitute a diagrammatic front elevation of the machine.

Fig. 12 is a fragmentary diagrammatic plan view, showing the relation of the press dial and certain controls.

Fig. 13 is a fragmentary elevation, showing a portion of the conveyor and press dial and taken in the direction of arrow 13 of Fig. 12.

Fig. 14 is an end elevation (taken in the direction of arrow 14 of Fig. 13) of the device for retaining the condenser parts in the conveyor work holders after they pass around the left end of the conveyor.

Fig. 15 which is a sectional view on line 15—15 of Fig. 13 shows details of an anti-rebound device AB.

Fig. 16 is a sectional view on line 16—16 of Fig. 17.

Fig. 17 is a view taken in the direction of arrow 17 of Fig. 16.

Fig. 18 is a view (partly sectional) on line 18—18 of Fig. 16.

Fig. 18A is a sectional view on line 18A—18A of Fig. 18.

Fig. 19 is a view in the direction of arrow 19 of Fig. 18.

Fig. 20 is a view in the direction of arrow 20 of Fig. 16.

Fig. 21 is a view in the direction of arrow 21 of Fig. 20.

Fig. 22 is a sectional view on line 22—22 of Fig. 13.

Fig. 23 is a view in the direction of arrow 23 of Fig. 22.

Fig. 24 is a fragmentary sectional view on line 24—24 of Fig. 10.

Fig. 25 is a fragmentary sectional view on line 25—25 of Figs. 10 and 11 combined.

Fig. 26 is a sectional view on line 26—26 of Fig. 11.

Fig. 27 is a plan view of lever 509 shown in smaller scale in Fig. 9.

Fig. 28 is a sectional view on line 28—28 of Fig. 27.

Fig. 29 is a fragmentary sectional view on line 29—29 of Fig. 9.

Fig. 30 is a view in the direction of arrow 30 of Fig. 29.

Fig. 31 is a side elevation of the mechanism shown in Fig. 7.

Fig. 32 is a side elevation of the mechanism at the right hand portion of Fig. 5, said view being taken from the opposite direction of the view shown in Figs. 7 and 31.

Fig. 33 is a fragmentary view in the direction of arrow 33 of Fig. 32.

Fig. 34 is a fragmentary sectional view on line 34—34 of Fig. 31.

Fig. 35 is a fragmentary sectional view on line 35—35 of Fig. 31.

Fig. 36 is a fragmentary elevation of a portion of the mechanism shown at the right of Fig. 5 and is taken in the right hand direction.

Fig. 37 is a fragmentary sectional view on line 31—37 of Fig. 36.

Fig. 38 is a side elevation of the can checking assembly, its drive shaft 22 being in section and its plunger guide tube 245 being in longitudinal section.

Fig. 39 is a view in the direction of arrow 39 of Fig. 38.

Fig. 40 is a sectional view on the line 40—40 of Fig. 38.

Fig. 41 is a view in the direction of arrow 41 of Fig. 38.

Fig. 42 is a side elevation of the tube checking assembly, its drive shaft 22 being in cross section and its plunger guide tube 285 being in longitudinal section, and a portion of the plunger 284 being in longitudinal section.

Fig. 43 is a view in the direction of arrow 43 of Fig. 42.

Fig. 44 is a sectional view on line 44—44 of Fig. 42.

Fig. 45 is a view in the direction of arrow 45 of Fig. 42.

Fig. 46 is a side elevation of the washer checking assembly, its drive shaft 22 being in cross section and its plunger guide tube 245' being in longitudinal section.

Fig. 47 is a view in the direction of arrow 47 of Fig. 46.

Fig. 48 is a sectional view on line 48—48 of Fig. 46.

Fig. 49 is a view in the direction of arrow 49 of Fig. 46.

Fig. 50 is a side elevation, partly in section, of the washer feeder assembly, said view being taken principally on line 50—50 of Fig. 52.

Fig. 50A is a fragmentary sectional view on line 50a—50a of Fig. 50 and drawn to a larger scale.

Fig. 51 is a plan view in the direction of arrow 51 of Fig. 50, the parts in section being on line 51—51 of Fig. 50.

Fig. 52 is a front elevation of the assembly in the direction of arrow 52 of Fig. 50.

Fig. 53 is a side elevation of the washer shaker assembly, its drive shaft 22 being in cross section.

Fig. 54 is a view in the direction of arrow 54 of Fig. 53.

Fig. 55 is a view, partly in section, on line 55—55 of Fig. 53.

Fig. 56 is a side elevation of the can feeder, its drive shaft 22 being shown in cross section.

Fig. 57 is a front elevation in the direction of arrow 57 of Fig. 56.

Fig. 58 is a fragmentary side elevation, showing the can hammer and a portion of its operating mechanism.

Fig. 59 is a fragmentary view in the direction of arrow 59 of Fig. 58.

Fig. 60 is a fragmentary view in the direction of arrow 60 of Fig. 56.

Fig. 61 is a sectional view on line 61—61 of Fig. 56.

Fig. 62 is a fragmentary sectional view of the can inverter which is drawn to a smaller scale in Fig. 64 and which shows the parts of the can inverted in positions differing from the positions shown in Fig. 62.

Fig. 63 shows a longitudinal sectional view of a hopper feed mechanism used on the can, tube and winding feeders.

Fig. 64 is a sectional view taken principally on line 64—64 of Fig. 57.

Fig. 65 is a plan view of a transfer mechanism used with the can feeder, tube feeder and winding feeder, the parts in section being on line 65—65 of Fig. 66.

Fig. 66 is a side view in the direction of arrow 66 of Fig. 65.

Fig. 67 is a bottom plan view of the device shown in Figs. 65 and 66 showing an additional device for use with the transfer device associated with the tube feeder and Fig. 67A is a bottom plan view showing an additional device for use with the transfer device associated with the winding feeder.

Fig. 68 is a side elevation of the tube feeder, the shafts which drive it being shown in cross section.

Fig. 69 is a side elevation of the winding feeder, the shafts which drive it being shown in cross section.

Fig. 70 is a plan view of the winding checker, the parts in section being on line 70—70 of Fig. 71.

Fig. 71 is a view in the direction of arrow 71 of Fig. 70.

Fig. 72 is a view in the direction of arrow 72 of Fig. 70.

Fig. 73 is a side elevation of a control mechanism supported within the table, the sheet metal enclosure of which is shown in section.

Fig. 74 is a fragmentary view in the direction of arrow 74 of Fig. 73.

Fig. 75 is a fragmentary sectional view on the line 75—75 of Fig. 73.

Fig. 76 is a sectional view on line 76—76 of Fig. 73.

Fig. 77 is a wiring diagram of the electrical controls.

Fig. 78 is a perspective view of can S.

Fig. 79 is a perspective view of the tube T.

Fig. 80 is a perspective view of the washer U.

Fig. 81 is a perspective view of the condenser winding W.

Fig. 82 is a perspective view of assembly V comprising wire X, metal disc Y and non-conducting washer Z.

Fig. 83 is a longitudinal sectional view of the assembled parts S, T, U and W.

Fig. 84 is a longitudinal sectional view of the work holder L and the parts of the press P which assemble parts S, T, U, W, together with assembly V.

Fig. 85 is a fragmentary view showing the condenser parts permanently assembled.

The machine includes a table A (Fig. 1) of box-like construction which supports channel irons Ch₁, Ch₂ and Ch₃ (see Fig. 22). Channels Ch₁ and Ch₂ (Figs. 24, 25, 26) support a conveyor B (Fig. 1) carrying a plurality of work holders w, a can feeder C, a can checker D, a tube feeder E, a tube checker F, a washer feeder G, a washer shaker H, a washer checker I, a winding feeder J, a winding

checker K and the mechanism for operating the conveyor B and the devices C to K in timed relation. C feeds a can S (Fig. 78) to a work holder w; E places an insulating tube T (Fig. 79) within the can; G feeds a spring-metal washer U (Fig. 80) within the tube; H shakes the washer down to the bottom of the can; and J places a condenser winding W (Fig. 81) within the tube so that the lower foil margin will rest upon the washer which electrically connects the lower foil margin with the can which serves as one of the condenser terminals.

As the work holders pass around the left conveyor sprocket, they invert the assembly as shown in Fig. 2. The assemblies are caused to be discharged singly into the work holders L on a rotary table or dial M which moves counterclockwise. The conveyor and assembling mechanisms are timed by the dial. The holder L has a hinged part L' (Fig. 84) which is opened so that the holder will receive a terminal assembly V (Fig. 82) which comprises a wire X passing thru a rubber-like washer Z and attached to a metal disc Y, which is to connect the wire X with the foil margin which is insulated from the can S. The assembly X is placed wire down and disc uppermost in an open holder. The holder is closed and it passes to a position where the other assembly parts of the condenser are discharged in inverted position from a work holder w of the conveyor. The open end of the can S fits around the disc Y and the washer Z. The assembly then passes under ram R of an hydraulic press P. Ram R is caused to descend in timed relation to the dial M while it is at rest, thereby forcing the circular edge of the can S (see Fig. 84) against a crimping surface of the work holder L which forces the can edge against the washer Z (see Fig. 85) compressing it and causing it to force the disc Y against the adjacent foil margin thereby forcing the other foil margin against the metal washer U and the latter against the can bottom, then uppermost. The permanently assembled condenser passes to a position where the work holder L opens and the condenser is discharged; and it gravitates down a chute AA (Fig. 1) and upon a conveyor BB which carries it to another machine where it is inspected and a terminal clip is attached to its lead wire X.

The press P, which is disclosed in Holmes and Gordon Patents Nos. 2,319,232 and 2,360,497, has an hydraulic cylinder Q (Fig. 1) which receives a piston to which the ram R is connected. A motor driven oil pump supplies oil under pressure to distributing valve which causes pressure oil to flow to one end of the cylinder Q or the other depending on the status of the valve. Another motor drives the table M intermittently and operates a cam which controls the distributing valve in such manner that, while the table is at rest, the ram R is forced down and then up.

Referring to Fig. 84, ram R supports a plate 800 to which screws 801 secure a ring 802 and a cylinder shell 803 which receives a piston 804 against which the pressure of fluid is applied. said fluid being pumped into the cylinder through suitable ducts including duct 805 in the plate 800. Piston 804 is recessed to receive the upper part of the work holder L and is so shaped as to cause the hinged part L' of the work holder to be forced toward the relatively fixed part so that a spring pressed ball 806 is forced against the can S, and the can S against the fixed part of the work holder. The condenser assembly is held vertical during the crimping operation.

As the ram R descends, the work holder L is clamped by the piston 804, and the can S is forced down against the annular groove 807 of the work holder by a plunger 808 (attached to the plate 800 by the ram R) which extends through a hole in the piston 804 which is sealed by a packing ring 809. The bottom edge of the can S is crimped against the washer Z as shown in Fig. 85. During this operation, the space between the piston 804 and the plate 800 decreases, pressure fluid passing out through duct 805 through a suitable pressure-relief valve. When the ram R rises, the condenser assembly is forced from the plunger 808 by a spring pressed ejector rod 810.

While the ram R descends and rises, table M and conveyor B are at rest and condenser parts S, T, U and W are being assembled. After ram R has risen and stopped, table M indexes and conveyor B moves while the condenser assembling devices and checkers are retracted from the conveyor B. The conveyor B and the condenser assembling devices and checkers are under control by table M which, as stated, is operated intermittently by an electric motor.

Can feeder

Referring to Fig. 64, base plate 1, supported by three channels Ch₁—2—3 on table A (Fig. 22), supports a frame 2 having rails 3, 4 which receive a work holder w as it moves horizontally and stops at the can loading station. A can S (Fig. 78) which is caused to descend in a manner to be described through a tube 5, is received on a plate 6 between the separated jaws 7 and 8 of a transfer mechanism (Figs. 65—66), said jaws being guided by rails 9 on plate 6. Jaw 8 is attached by pin 10 to a lever 11 having a slot 12 receiving a pin 13 attached to a lever 14 pivoted on a pin 15 supported by a bracket 16 attached to plate 6. A spring 17 attached to bracket 16 and lever 14 urges the lever clockwise (Fig. 64). Jaw 7 is attached to rods 18 (Fig. 65) passing through jaw 8 and surrounded by springs 19 which urge jaw 8 toward jaw 9. The jaw 8 is separated from jaw 7 in Fig. 64 because lever 11 engages tube 5 and cannot move counterclockwise because its slot 12 receives pin 13. When jaw 7 is moved left, to engage jaw 8, the cam is clamped between the jaws, and with spring pressure when jaws 7 and 8 move left together to bring the cam under a plunger 20. Jaw 8 can be retracted from jaw 7 by moving lever 14 counterclockwise.

Jaw 7 is operated by a mechanism which includes a cam 21 (Fig. 56) operated by a shaft 22 engaged by a roller 23 on a lever 24 which a spring 25 urges toward the cam. Lever 24 is attached to a shaft 26 (Fig. 64) supported by frame 27 and connected with a lever 28 connected by a link 29 with jaw 7. The same kind of transfer mechanism (Figs. 65—66) is used with the tube feeder E and with the winding feeder J with certain additions noted hereinafter.

The mechanism for operating plunger 20 comprises a cam 30 driven by shaft 22 and engaged by a roller 31 on a lever 32 pivoted at 33 and connected by a link 34 with a lever 35 pivoted at 36 on a bracket 37 supported by frame 27. Lever 35 has arms which support pins 38 slidably received by grooves 39 (Fig. 6) in a block 40 attached to plunger 20. A spring 41, attached to link 34 and to a pin 42 carried by a plate 43 supported by frame 27, urges roller 31 against cam 30. The tube feeder and the winding feeder have trans-

fer plungers which are operated in the same manner.

The hopper feeds for the can, tube and winding feeders are the same. Referring to Fig. 63, a hopper 50 is supported by a base 51 attached to plate 43 which is braced by parts 44 and 45 (which serves as a guard) attached to a bracket 46 supported by a frame 47. Plate 43 carries brackets 52 which support a tube 53 surrounded by a tube 54 having a collar providing a groove 55 which receives a plate 56 supporting pins 57 and 58 guided by hopper base 51. Tube 54 is reciprocated for the purpose of agitating the parts (cans, tubes or windings) in the hopper so that one of the parts will enter the tube 54 when it is lowered. The tube 54 is reciprocated by a mechanism which includes a lever 60 (Fig. 64) pivoted at 61 on a bracket 62 carried by plate 43 and carrying pins 63 received by groove 55 of tube 54. A link 64 is connected with lever 60 and supports, at its lower end, a ball bearing 65 (Fig. 61) journalled on a screw-stud crank pin 66 threaded into a plate 67 which is integral with a shaft 68 journalled in ball bearings 69 and 70 supported respectively by frame 47 and a plate 71 attached thereto. A washer 72 recessed to receive the head of stud 66 bears against the inner race of the bearing. Ring 65a attached to link 64 retains the bearing outer race. Screws 73 attach disc 67 to a gear 74 meshing with a gear 75 attached to a shaft 76 journalled in a ball bearing 77 carried by frame 47. Frame 47 supports a bearing 78 for the shaft 22 which drives cams 21 and 30 (Fig. 64). The mechanism shown in Fig. 61 is the same for the hopper feeds associated with the can, tube and winding feeders.

Referring to Fig. 64, tube 53 is connected with a chamber 80 provided by a body 81 having a hinged door 82 carrying a pin 83 for engagement by a latch 84 rotatable by a knob 85 pivotally supported by the body (see Fig. 59). A tube 86 connects the body 81 with the tube 5. As a can descends through tube 53, it engages a plunger 93 guided by a bracket 91 supported by plate 43 and urged left and up by a spring 92. Plunger 90 can be retracted by clockwise rotation of a lever 93 engaging a notch in the plunger. Lever 93 is pivoted at 94 on a part of bracket 91 and has a slot 95 receiving a pin 96 carried by a lever 97 pivoted at 97a on bracket 91 and having a pointed arm 98 for engaging the can. Arm 98 serves only as a stop when the can descends bottom down; but, if it descends top down, the hook on arm 98 engages inside the can for the purpose of inverting the can while in the chamber 80 as shown in Fig. 62. Lever 97 is connected by link 99 with a bell crank lever 100 pivoted at 101 on a bracket 102 attached to plate 43. Lever 100 has an eye 103 through which there passes a rod 104 surrounded by a spring 105 held under compression by a washer 106 and a cotter-pin 107. The lower end of rod 104 is attached at 108 to an arm 28a of lever 28. Each time the jaws 7, 8 of the transfer mechanism move left, plunger 90 and arm 98 move right and lever end 93a moves left to catch a can dropping from plunger 90 (see Fig. 62) while a can released from arm 98 descends through chamber 80 and tubes 86 and 5 and is stopped by the top of jaw 7 then to the left of the position shown in Fig. 64. When the jaws 7 and 8 move right the parts 90 and 98 move left and 93a moves right. Between the parts 90 and 93a, tube 53 has an opening 110 (Fig. 59) for receiving a hammer head 111 carried by a leaf spring 112 fixed to a clamp hub 113 attached to

a shaft 114 journalled in bearings 115 (Fig. 58) supported by a tube 116 fixed to plate 43 and attached to a lever 117 which is attached to a rod 118 (Fig. 64) coupled at 119 to a rod 120 which passes through a hole in a bracket 121 attached to frame 47. Rod 120 carries a plate 122 for engagement by a pin 123 carried by cam 30 (Fig. 64). Once during each revolution of cam 30 clockwise, pin 123 lifts rod 120 and thereby effects retraction of hammer 111 from tube 53. After pin 123 leaves plate 122, rods 118, 120 descend to cause the hammer 111 to strike a can adjacent the opening 110 so as to dislodge the can from a can just above it, in case the bottom end of the upper can would telescope slightly into the open end of the lower can.

Referring to Fig. 68, lever 32' (same as lever 32 of Fig. 64) has a lug 130 for engagement by a stop screw 131 carried by a bracket 132, mounted on plate 1. Screw 131, which is secured in adjusted position by a lock nut 133, determines the movement of lever 32' clockwise, and provides an adjustment for the descent of plunger 20' (same as plunger 20 in Fig. 64).

Tube feeder

The tube feeder E shown in Fig. 68 is substantially like the can feeder with the following exceptions. There is no mechanism for causing the tubes T to drop one at a time upon jaw 7 (when to the left) since the weight of a column of tubes in feeder tube 53' (directly connecting the hopper with tube 5) is not sufficient to interfere with proper operation. The lower end of plunger 20' is provided with a boss 20'a and a flange 20'b for engagement with the upper end of a tube.

The transfer mechanism used with the tube feeder uses a can positioner shown in Fig. 67 which comprises a block 850 attached to the underside of plate 6' (Fig. 68) and adjacent the hole 851 into which the can S drops. Can S is urged against block 850 by a plate 852, having a V-notch to receive the can, by a spring 853 surrounding a rod 854 attached to plate 852 and guided by a bracket 855 attached to plate 6'. Block 852 is guided by rails 856 and has a slot 857 which receives a pin 858 attached to jaw 7' and depending therefrom. As the tube T clamped between jaws 7' and 8' moves right (Fig. 68), the can S is held vertical upon the conveyor work holder w by the plates 850 and 852, preparatory to the descent of the tube T into the can S by the plunger 20'. As the jaws 8 and 7 move right to receive another tube T, plate 852 is moved right to the position shown in Fig. 67.

Winding feeder

The winding feeder J shown in Fig. 69 is substantially like the can feeder with the following exceptions. Tube 53'' has a restriction in internal diameter beginning at x. The mechanism for allowing one winding to drop at a time upon jaw 7 (when at the left) comprises a plunger 140 guided by a block 141 attached to plate 43'' and urged left by a spring 142. Plunger 140 has a cylindrical head 140a for engagement with windings; and it is notched to receive a lever 143 pivoted at 144 and engageable by a shoulder 145 of a bar 146 guided by block 141. Bar 146 is connected with a bell crank lever 147 pivoted at 148 on a bracket 149 attached to plate 43. Lever 147 carries an eye 150 through which there extends a rod 151 surrounded by a spring 152 confined in compression between the eye 150 and a

washer 153 retained by a pin 154. Rod 152 is attached to arm 28'a which moves with the transfer jaws 7 and 8. When the jaws move left, bar 146 is retracted from the windings in tube 53" and plunger 140 is pressed against the windings by the head 140a of plunger 140. The winding that had been supported by plunger 140 descends upon jaw 7". When the jaws move right, bar 146 moves left and plunger 140 moves right. In case plunger 140 should engage the side of a winding, it will stop moving but the winding will not be injured since the force moving the bar 146 left is applied yieldingly through the spring 152. Force is applied yieldingly to plunger 20" from lever 35" through a spring 149 confined 15 between a shoulder of plunger 20" and the grooved block 40" which is slidable upon the plunger 20".

The transfer mechanism used with the winding feeder uses a can positioned as shown in Fig. 67A which is like the one for the tube feeder shown in Fig. 67 with the addition of a winding positioner which holds the winding W concentric with the tube T in can S while the winding W is being forced down by the plunger 20" (Fig. 69). The winding positioner comprises a lever 860 pivoted at 861 and located in a recess 862 in plate 6" so that the lower surface of the lever is flush with the lower surface of the plate. A spring 863 urges the lever 860 counterclockwise so that, as the winding W descends, its lower edge enters between the lever 860 and the U-notch 864 of plate 6". Thus the winding W is guided into the tube T in the can S. The plunger 20" pushes the winding W below the under surfaces of the lever 860 and the plate 6".

Washer feeder

The washers U (Fig. 80), strung on double wires 160 (Fig. 52) are supported ready for use in tubes 161 supported on a bracket 163. When feeder magazine tube 164 is becoming empty, a tube 161 is inverted over it and washers therein gravitate within the tube 164 to fill it. Tube 164 is supported upon a tube 165 and is braced by a post 166 supported by a frame 167 which also supports tube 165. The feeder is operated by a cam 170 (Fig. 50) driven by shaft 22 which is supported by a bearing 171 carried by a bracket 172. Cam 170 is engaged by a roller 173 carried by a lever 174 having a hub 175 pivoted on a screw 176 threaded into bracket 172. A spring 177 urges the lever 174 clockwise. Lever 174 is connected by a link 180 with a bar 181 supported for horizontal movement by frame 167 and retained by a block 182 which guides also a blade 183a connected with a pin 184 attached to bar 181 and extending through a slot 185 in frame 167 and into a slot 186 in a V-jaw 187 supported for horizontal movement by frame 167 and urged right by a spring 188. As bar 181 moves right, jaw 187 moves against the condenser assembly to force its can against a fixed block or jaw 189.

As shown in Fig. 50A, the stack of washers in tubes 165 and 164 is supported by a rod part 183 attached to block 182 and supporting the blade 183a. Blade 183a which is normally to the left of the lowermost washer on part 183 has a shoulder 183b (Fig. 50A) stepped up the thickness of the washer. When blade 183a is moved right by cam 170, the blade shoves out to the right only the lowermost washer and causes it to fall through a hole in a block 190 and a hole 191 in the plate 167a of frame 167. In case of a jam, the block 190, hinged at 191

can be swung away from the tube 165. A slide 192 can be raised against the spring pressed plunger 193 by turning an eccentric 194 on a shaft 195 having a handle 196 and pivoted in bearings provided by a bracket 198. When the handle 196 is turned down the slide 192 is raised, and when handle 196 is turned up as shown in Fig. 52 the slide is lowered but only to the extent determined by a set screw 199 locked by a nut 200. This adjustment determines the gap between the lower end of the slide and the rod part 183 which supports the washer. This gap is sufficient only to allow one washer to pass through.

Washer shaker

Referring to Figs. 53, 54 and 55, the shaker is built like an electrical buzzer and is contained in case 211 and has a vibratory element 212 providing a loop which can surround the condenser can and shake it to make sure that the washer discharged from the washer feeder has descended to the bottom of the can. Case 211 is attached to a plate 213 carried by a lever 214 attached as shown in Fig. 55 to a shaft 215 journaled in bearings 216 supported by a block 217 mounted upon a base plate 218 which supports bars 219 between which the vibrator case 211 is movable. These bars support a cover 219A (Fig. 3). Shaft 215 is attached to a lever 220 carrying a roller 221 for engaging a cam 222 driven by shaft 22. A spring 223 connecting the lever 214 with the plate 218 urges the roller 221 against the cam 222. Downward movement of lever 214 is limited by a stop 224. A block 225 carried by lever 214 engages a plunger 226 of a switch SW1 when the cam 222 is in the position shown to close the switch which effects operation of the vibrator for a brief period. During the major portion of rotation of the cam 222, the vibrator is up and non-operating. The flat on cam 222 allows the spring 223 to pull the lever 214 counterclockwise to cause the loop 212 to be located around the can S and to cause the switch SW1 to be closed.

Can checker

Referring to Figs. 39 to 41, the can checker comprises a base plate 230, supporting a post 231, a bracket 232 and a bar 233. Bar 233 supports bearing 234 for shaft 235 fixed to levers 236 and 237. Lever 236 carries a roller 238 for engaging a cam 239 driven by shaft 22. Spring 240 connected between post 231 and lever 236 urges the latter counterclockwise. Bar 233 supports a screw 241 providing a pivot for a lever 242, the left end (Fig. 38) of which carries a pin 243 received by an aperture in a rod 244 guided by a tube 245 provided by bracket 232. The lower end of rod 244 enters the top of the condenser can and a shoulder 244a is engageable with the top edge of the can. The lever 241 may engage a screw 250 carried by a lever 251 pivoted on bracket 232 at 252 and urged by a spring 253 against a stop screw 254. When lever 251 is in the normal position shown in Fig. 38, it holds down the plunger 255 of a switch SW8 to maintain the latter open. If the top of the condenser can is too low or no can is present, stop screw 250 will be engaged by lever 241 and lever 251 will rotate counterclockwise and switch SW8 will close. If the top of the condenser can is higher than the allowable limit, switch SW8 will be caused also to close by the lifting of the right end of lever 251 by the engagement with a stop screw 256 on lever 251 by a floating lever

11

257 which is part of an articulated link connecting levers 231 and 241 and comprising link member 260 (which is adjustable in length), link member 261 and two parallel bars, one being lever 257 and the other the part 262. A spring 263 urges levers 231 and 241 toward one another and tends to maintain the articulated link in the status shown in Fig. 38. If the can is too long, rod 244 cannot descend as far as it should. When cam 239 allows the lever 236 to move counterclockwise to the fullest extent, lever 231 will move down relative to lever 241 far enough to cause lever 257 to engage the screw 256 and to lift the right end of lever 251 so that switch SW8 will close.

Tube checker

Referring to Figs. 42-45, the tube checker comprises a base plate 270 supporting a bracket 271 and a bar 272 which supports bearings 273 for a shaft 274 attached to a lever 275 carrying a roller 276 engageable with a cam 277 driven by shaft 22. Shaft 274 is attached to arm 278 connected by link 279 with lever 280 pivoted on a screw 281 threaded into bar 273. A spring 282 urges levers 278 and 280 counterclockwise. The left end of lever 280 carries a pin 283 received by a hole in a rod 284 guided by a tubular part 285 of bracket 271. Rod 284 carries a feeler rod 286 and a feeler lever 287 pivoted at 288 on the rod 284 and connected at 289 with a rod 290 passing through the rod 284 and surrounded by a spring 291 retained by a washer 292 and a pin 293. Spring 291 urges the feeler 287 clockwise. Feeler 287 passes between parts 294 and 295 carried by part 285. The upper end of 287 is free to engage a roller 296 on a spring blade 297 engageable with the plunger 298 of a switch SW9 carried by a bar 299 having slots 300 for receiving screws 301 threaded into a part 302 of bracket 271. The bar 299 can be adjusted along the screws 301 by turning a screw 304 threaded through a lug 303 of part 302 and secured in adjusted position by a nut 305. The locator of switch SW9 having been adjusted so as to locate the roller 296 properly relative to feeler lever 287, if tube T is not present, switch roller 296 will be engaged by lever 287, therefore switch SW9 will close.

Washer checker

Referring to Figs. 46-48 as well as Figs. 38-41 it will be seen that the washer checker is similar to the can checker with the following exceptions: Plunger rod 244 carries a spring loaded can centering device 306 for holding the can vertical while the plunger descends. As will be apparent from consideration of the can checker, the switch SW10 of the washer checker will be closed if there is no washer U in the can or if the washer is not in proper position in the can, for example, cocked on one side.

Winding checker

Referring to Figs. 70-72, the winding checker has a bracket 310 supporting shaft 22 which drives a cam 311 for engaging a roller 312 carried by lever 313 fixed to a shaft 314 journalled in bearings provided by a bracket 315 attached to bracket 310. A spring 316 urges lever 313 clockwise (Fig. 71). Lever 313 carries a feeler 317 for engaging the winding in the can. If the winding is not present, lever 313 passes on a roller 318 on a leaf spring arm 319 which operates a switch SW11 to close it. Too high a winding is detected

12

by a mechanism shown in Figs. 70 and 72. A shaft 320 journalled in a bracket 321 is attached to levers 322 and 323. A spring 324 attached to lever 323 and bracket 321 urges the shaft 320 counterclockwise (Fig. 72). Lever 322 carries a feeler 325 for contacting the winding which, if too high (long), raises lever 323 to such extent that the plunger of a switch SW12 moves up to cause the switch SW12 to close.

Transfer of condenser assembly from conveyor to work holder of press table

Referring to Fig. 13, as the work holders pass counterclockwise around the left end of the conveyor, the condenser in the holders are retained by a curved bar 330 supported by brackets 331R, 331L (Figs. 14, 16 and 17) and 332R, 332L supported by the conveyor channel bars Ch₁ and Ch₂. At the transfer station TS (Fig. 13), a condenser can S is received between spring actuated jaws 333 and 334 and a fixed jaw 335 (Fig. 18). These jaws are supported by the bar 330 in the manner shown in Figs. 18 and 19. A plunger 350 (Fig. 16), guided between rails 351 (Figs. 20-21) attached to a bracket 352 supported by the conveyor channels (Fig. 17), is caused to descend to push the condenser from a work holder w (Fig. 15) of the conveyor to a work holder L of the press dial M. This plunger is actuated by a lever 353 (Fig. 16) fixed to a shaft 354 supported by channels Ch₁ and Ch₂ (Fig. 22) and attached to a lever 355 (Fig. 23) connected by a link 356 (Figs. 22-23) with a lever 357 pivotally supported at 358 upon a bracket 359 and carrying a roller 360 for engaging a cam 361 driven by shaft 22. Springs 362 urge lever 356 clockwise (Fig. 22) and shaft 354 and lever 353 counterclockwise (Fig. 23). This movement is assisted also by springs 363 attached to a lever 364 fixed to shaft 354. Thus the work is ejected from the conveyor by spring force.

Conveyor B

Conveyor B comprises an endless chain 370 passing around a drive sprocket 371 (Fig. 10), over a center, idle sprocket 372 (Figs. 10-11), around an end idle sprocket 373 (Fig. 11) and under a slack take-up sprocket 374 carried by a lever 375. Slack is taken up by turning a screw 376 threaded in lever 375 until it strikes the plate 1 of the can feeder mechanism. Screw 376 is fixed by a lock nut 377. The chain 370 slides on plates 380 and 381. The work holders w are grooved to receive rails 3 and 4 (Fig. 64) located at the can feeder, tube feeder and winding feeder as shown in Figs. 10 and 11.

Sprocket 371 is fixed to a shaft 389 journalled in bearings 390 and 391 supported by channel Ch₁ and Ch₂ respectively (Fig. 24). Shaft 389 is fixed to a gear 392 meshing with a gear 393 fixed to a shaft 400 journalled in a bearing 394 mounted in a bracket 396 supporting also bearing 390 and journalled in a bearing bracket 397 (Fig. 25) which supports also a bearing 398 for a shaft 399 journalled also in a bearing 401 supported by a bracket 402. Brackets 397 and 402 are attached to channels Ch₁ and Ch₂ respectively (Fig. 25). Shaft 399 supports center, idle sprocket 372. Shaft 400 is journalled also in a bearing 403 (Fig. 37) supported by a bracket 404 which, as shown in Fig. 26, supports also a bearing 405 for a shaft 406 carrying end idle sprocket 373 and journalled also in a bearing 407 mounted in a bracket 408. Brackets 404 and 408 are attached respectively to channels Ch₁ and Ch₂. Shaft 406

carries a brake-drum 410 engaged by a brake-shoe 411 carried by a rod 412 urged down by a spring 413. Spring 413 surrounds the threaded portion of the rod 412 and receives nuts 414 against which the spring presses. Nuts 415, 416 are threaded on the upper end of the rod which is supported by bracket 407. Fig. 26 shows guards 417, 418 around the chain 370 and a guard 419 partly enclosing the brake-drum. Nuts 414 provide spring adjustment. Nut 415 serves as a guide for rod 412.

Conveyor, cam-shaft and agitator drive

Referring to Fig. 31, an electric motor M3 is connected by a speed reducer 425 with a shaft 426 which drives a sprocket 427 connected by a chain 428 with sprockets 429, 430 and 431. Sprocket 429 rotates continuously while motor M3 runs and drives the agitator shaft 76 (Figs. 60, 61 and 64) which operates the agitators of all of the hopper feeds.

Referring to Fig. 34, sprocket 430 is connected to the driving member 435 of a $\frac{1}{3}$ turn clutch C1 having a driven member 436 keyed to a shaft 437 journalled in bearings supported by a bracket 438 and bushing 439 secured to a plate 440 attached to a base plate 440a. Shaft 437 drives a sprocket 441. Clutch C1 has a lever 442 (Fig. 31) pivoted at 443 on member 436 and having a lug 444 adapted to engage a notch 445 of member 435. A spring 446 urges lever 442 counterclockwise about its pivot 443. Lever 442 is prevented from connecting members 435 and 436 by engagement of a lever 447 pivoted on a rod 448 extending from the plate 440. Lever 447 has a hook 449 engaging a notch 450 in member 436 to stop rotation of the latter. Lever 447 is urged into the position shown by a spring 451 surrounding a rod 452 pivotally connected at 453 with a latch lever 454 pivoted on rod 448 and having a notch 455 engaged by or engageable with a latch pawl 456 attached to a shaft 457. Rod 452 passes through a block 460 which is swivelledly supported at 461 by lever 447 and receives nuts 462 and 463, the latter being normally spaced from the block 460. Spring 451 is confined under compression between the block 461 and the eye member 452a of rod 452. When, by clockwise rotation of shaft 457, the latch pawl 456 is retracted from the notch 455 of lever 454, spring 452 is released to allow nut 462 to engage block 460, and lever 454 falls by gravity to retract lever hook 449 from notch 450 and spring 446 is permitted to move lever lug 444 into a notch 445 of driving member 446 to connect the clutch members 435 and 436, so that shaft 437 and sprocket 441 will turn counterclockwise as viewed in Fig. 31. Shaft 437 turns until a roller 465 (Fig. 34) pivotally supported by member 436 engages a lever 454' (like 454) to cause it to move counterclockwise about its pivot rod 448' thereby causing (through the action of a spring 451') counterclockwise rotation of a lever 447' to urge the same against the periphery of member 436 so that the hook end 449' of lever 447' will snap into the notch 450 of member 436 at the end of $\frac{1}{3}$ turn thereof and consequently lever 442 will be rotated clockwise about its pivot 443 by virtue of engagement of the lever 442 with the hook end 449' of lever 447'. Movement of lever 454' counterclockwise also effects the engagement therewith of a pawl 456' which at that time is being urged counterclockwise by means to be described. Subsequent clockwise rotation of pawl 456' causes the clutch to be tripped (reengaged) for $\frac{1}{3}$ turn when

stopped by the cooperation of similar parts marked with the same numbers but with double primes affixed. The clutch C1 is therefore under control by three pawls 456, 456' and 456'' mounted respectively on shafts 457, 457' and 457'' which are concurrently rotated by means to be described.

Sprocket 441 (Figs. 34 and 36) drives a chain 470 which drives a sprocket 471 supported on a hub 472 (Fig. 37) but not directly attached thereto. Hub 472 provides a friction disc 474 and supports pins 475 extending into holes in friction disc 476. A hex-nut 477 is threaded on hub 472 which has a hexagonal periphery (indicated in Fig. 37). By holding hub 472 with a wrench so that it will not turn the nut 477 is tightened by another wrench so as to provide a frictional drive between the sprocket 471 and hub 472 and the conveyor drive shaft 400 to which the hub is attached. If the conveyor jams, sprocket 471 can slip to prevent breakage. The conveyor will be out of time after the cause of jamming is removed. Nut 477 is loosened and the correct timing relation is reestablished and the nut 477 is tightened while shaft 400 is prevented from turning by applying a wrench to hub 472.

Fig. 35 shows that plate 440 supports a bushing 480 supporting bearings for the shaft 16a driven by sprocket 429 and connected with shaft 16 by a coupling 481. Sprocket 431 (Figs. 31 and 35) is connected by a one-turn clutch CII with a shaft 22a journalled in bearings provided by a bracket 482 and the plate 440. A coupling 483 connects shaft 481 with cam shaft 22. Clutch CII is made like clutch C1 except that it has only one trip and stop mechanism. The parts are marked with the same numbers as the corresponding parts of clutch C1 with triple primes affixed. As the levers 454', 454'' and 454''' cannot gravitate (as lever 454 does) to clutch tripping positions, such motion is obtained by springs 464', 464'' and 464''' respectively.

The control of the latch pawls 456, 456' and 456''' of the clutch trip mechanisms will now be described with reference to Fig. 32 which shows that side of plate 440 opposite to that shown in Fig. 31. Shafts 457, 457' and 457'' which carry pawls 456, 456' and 456'', respectively, are attached to levers 486, 486' and 486'', respectively, connected by links 487, 487' and 487'' with a plate 488 which, as shown in Fig. 34, is journalled on a roller bearing 489 carried by bushing 439. Plate 488 is rotated clockwise (Fig. 32) by a latch lever 490 pivoted at 491 on plate 488 and counterclockwise by a spring 492 attached to an arm of lever 490 and to a lever 493 pivoted on plate 440 at 494 and carrying a roller 495 for engaging a 9-tooth cam disc 496 attached to shaft 400.

Latch lever 490 has a hook 500 for engaging an arm 501 of a lever 502 pivoted on a post 503. As shown in Fig. 9, lever 502 is connected by a link 504 with a lever 505 attached to a shaft 506 (Fig. 29) supported by bearings 506a and 506b mounted in brackets 506c and 506d, respectively. To shaft 506 there is attached a lever 507 connected by a link 508 with a lever 509 pivoted at 510 and urged clockwise by a spring 511 so that a roller 512 carried by the lever 509 will engage the periphery of the hydraulic press dial and will drop into a notch 513 thereof (located at each dial work-holder) when the dial stops. When roller 512 drops into a notch 513, links 508 and 504 move right (Fig. 9) and arm 501 of lever 502 is located in the position

shown in Fig. 32 which it occupies to cause the clutch C1 to become disengaged. Therefore the conveyor does not move while the press dial is at rest. When the press dial starts turning, lever arm 501 moves up in Fig. 9 or left in Fig. 32 to effect clockwise rotation of plate 488 to trip (engage) the clutch C1 which rotates $\frac{1}{2}$ turn and causes (by the 3 to 1 chain drive) $\frac{1}{2}$ turn of shaft 400 which causes the conveyor to move its work holders a distance equal to the linear spacing of the work holders. As shaft 400 turns, cam 496 brings one of its teeth into engagement with roller 495 to effect counterclockwise rotation of lever 493 and of an unlatching lever 520 (pivoted at 521 on plate 440) and connected with lever 493 by link 522. Lever 520 carries a roller 523 for engaging the lever 490 to unlatch the same from lever arm 501. So long as roller 523 remains up, the arm 501 and the latch lever 490 cannot be reconnected and the conveyor cannot start.

To make sure that the conveyor does not start before the mechanisms operated by cam shaft 22 have at least been retracted from the work on the conveyor by the operation of cams on the cam shaft, the roller 523 is held up by the engagement of a pin 525 on lever 520 with a latch lever 526 pivoted at 527 on plate 440 and connected with a rod 528, the upper end of which is guided by a bracket 529 attached to plate 440. A spring 530, attached to the rod 528 and to the plate 440, urges the rod 528 down and the lever 526 down against the pin 525. Therefore when, due to cam 496, lever 520 is moved counterclockwise to raise lever 490, pin 525 will be caught by latch lever 526. Lever 526 will not release pin 525 until rod 528 is raised. This is effected, after the mechanisms operated by shaft 2 have been retracted from the work on the conveyor, by the counterclockwise rotation of a pin 531 carried by a cam 532 driven by shaft 22 which engages a lug 533 of rod 528 to lift it and the latch lever 526.

The normal or at-rest position of cam 532 is indicated at 532' when a notch thereof receives a spring loaded roller 535 (then at 535') carried by a rod 536 attached at 537 to a lever 538 pivoted at 539, thus supporting rod 536 near its upper end, its lower end being supported by a bracket 540. The spring load is applied by a spring 541 which surrounds the rod 536 and is held under compression between bracket 540 and a shoulder 542 of the rod. The cam shaft 22 is held in a definite position while the clutch C1 is not engaged.

Clutch C2 is under control by cam 496 which, after the conveyor has stopped, causes a roller 550 on a lever 551 (pivoted at 552 on plate 440) to move left against the action of a spring 551a, and a link 553 and a lever 554 to move right to effect clockwise (in Fig. 32) or counterclockwise (Fig. 31) rotation of shaft 457''' and trip latch pawl 456''''. When clutch C2 is tripped, the cam shaft 22 turns one revolution and causes the plungers of the can, tube and winding feeders to go down and up while the conveyor is at rest.

Fig. 15 shows an anti-rebound device located at the transfer station. When a condenser assembly drops from the conveyor work holder upon a dial work holder, any tendency to bounce from the latter is counteracted by a leaf spring 560 which engages the cans and is urged against the can by virtue of pressure applied by a spring 561 which urges clockwise (Fig. 15) the lever 562 which carries the spring 560. Lever 562 is piv-

oted at 563 on a bracket 564 mounted on channel Ch1.

Electrical control system

- 5 Referring to Figs. 73-76, the table A supports a start-stop switch unit PB1 having a start switch 600 and a stop switch 601 (also Fig. 77). A lever 602, pivoted at 603 on a bracket 604 attached to the table A, carries a lug 605 which opens stop switch 601 when the lever 602 is located as shown in Fig. 73. Lever 602 is connected to a link 607 guided by a bracket 608 and urged right by a spring 609 thereby "breaking" toggle links 610, 611. Link 611 is pivoted at 612 on a plate 616 attached to table A. The pin 613 connecting links 607 and 610 is attached to a lever 614 pivoted at 615 on plate 616. Plate 616 supports a solenoid Sol 1 having an armature 617 urged down by a spring 618 and movable upwardly, when the solenoid is energized to engage a screw 619 carried by link 611 in order to disalign the links 610, 611 so that spring 609 will complete their movements to the "toggle-break" position shown in Fig. 73.
- 10 25 A plate 620 carries a solenoid control switch SW13 having a plunger 621 urged upwardly by a spring not shown so that the switch is biased closed. Plunger 621 is engaged by a lever 622 pivoted at 623 on plate 620 and engaging a pin 624 when the plunger 621 is up and the switch SW13 is closed. Lever 622 has a notch 625 and an inclined surface 626 which cooperates with a point 627 and an inclined surface 628 of a bar 629 received by a notch 630 in a plate 631 attached to plate 620. Bar 629 is attached at 632 to a lever 633 pivoted on plate 620 at 634 and connected by link 635 with link 607.
- 30 35 To start the machine, lever 602 is pulled counterclockwise from the position shown in Fig. 73. This causes point 627 of bar 629 to engage the left end surface of the notch 625 of lever 622 which then moves counterclockwise to open switch SW13. The counterclockwise movement of lever 602 continues after the plunger 621 is entirely down and the engaging surfaces of point 627 and left end of notch 625 are inclined to the left away from the vertical center line of pivot 623. Thereafter, the further pull by lever 602 on bar 629 causes point 627 to receive a reaction-force-component causing the bar 629 to move up and disengage the lever 622; and switch SW13 closes. The left movement of lever 602 permits the stop switch 601 to close so that the machine can be started by pressing the button of start switch 600. Toggle links 610, 611 straighten out with the axis of their connecting pin 610a below the line connecting the axes of 613 and 612.

40 45 Referring to Fig. 77, a switch SW1 connects wires 641, 642 and 643 with a source of three-phase alternating current. Motor M1, which drives the hydraulic pressure pump for the press P, is connected with wires 641, 642 and 643 by a manual reset thermal overload switch SW2. A relay R6 has a magnet coil 644a which when energized closes contact 644. Coil 644a is energized and the contact 644 is closed while the motor M1 is running.

45 50 Motor M2, which drives the dial M of press P and controls the hydraulic valve of the press P for effecting movements of its ram in timed relation to operation of the dial M, is connected with wires 641, 642 and 643 by contacts 651, 652 and 653, respectively, of an electromagnetic switch PR1 having a magnet coil 649 for attracting an armature 640a against the action of a

spring 640b to close said contacts and also another contact 654, all of the switch contacts being insulatingly connected with the armature 640a. Two of the wires leading to motor M2 include heater coils 645a and 646a, respectively, for opening thermal switches 645 and 646, respectively, when the motor is overloaded. The press P with its pump motor M1 and its dial motor M2 is disclosed in the patents to Holmes and Gordon Nos. 2,319,232 and 2,360,497.

Motor M3 is connected with wires 641, 642 and 643 by the contacts 651', 652' and 653' of an electromagnetic switch PR2 having a magnet coil 650 which when energized effects the attraction of an armature 650a against the action of a spring 650b to close contacts 651', 652' and 653' and also another contact 654', said contacts being insulatingly attached to armature 650a. Two of the wires connected with motor M3 include heater coils 647a and 648a, respectively, for effecting the opening of thermal switches 647 and 648, respectively, when motor M3 is overloaded.

There is a relay R5 having a magnet coil 683 connected with two of the wires leading to motor M3. When motor M3 is running, coil 683 is energized to effect the closing of the relay contacts 682.

There is a start-stop switch PB1 having a normally open start button switch 600 and a normally closed stop button switch 601. Switch PB1 is connected with wire 643 and with an emergency stop switch PB2 connected with operator's safety switch SW4 connected by wires 651 with one end each of the coils 640 and 650. The other ends of each of the coils 640 and 650 are connected with a wire 656 connected with thermal switch 648 connected with thermal switch 647 connected with thermal switch 646 connected with thermal switch 645 connected with contacts 644 of relay R6 connected with wire 641.

The machine is started by closing switch SW1 to connect wires 641, 642 and 643 with the current source. Switch SW2 is then closed to cause motor M1 to operate. Relay R6 closes its contacts 644. Therefore when start switch 600 is closed, the magnet coils 640 and 650 become energized through the following circuit: wire 641, contacts 644, switches 645, 646, 647, 648, magnet coils 650 and 640 in parallel between the wires 656 and 657, safety switch SW4 closed, emergency stop switch PB2 closed, stop switch 601 closed, switch 600 then closed, wire 643. The coils 640 and 650 being energized, motors M2 and M3 are connected with wires 642 and 643 and switch 600 is by-passed by wire 658, contact 654' closed, wire 655, contact 654 closed, wire 643. Both contacts 654 and 654' must be in closed position in order to by-pass the switch 600. Therefore the switch 600 may be released and the magnet coils 640 and 650 will be energized. These coils will be deenergized by the opening of any of the thermal switches 645, 646, 647 and 648 or by the opening of the operator's safety switch SW4 or by the opening of the emergency stop switch PB2 or by the opening of the stop switch 601 provided its by-passing switch SW5 is open. Since it is desirable to have the machine ordinarily stopped when the dial comes to rest, provisions are made for the control of switch SW5 in a manner to be described.

Switch SW4, as shown in Fig. 12, has a lever 660 carrying a roller 661 to be engaged by an arm 662 of lever 663 pivoted at 664 and urged by a spring 665 against a stop 666. If the press

operator should inadvertently allow his hands to move too far toward the transfer station TS, his hand will push lever 663 clockwise to move lever 660 of switch SW4 clockwise to open said switch. 5 The opening of switch SW4 or emergency stop switch (PB2 located above switch PB1 in Fig. 1) causes deenergization of coils 640 and 650 (Fig. 77) of switches PR1 and PR2 respectively to cause motors M2 and M3 to stop and operation of 10 the dial, chain conveyor and assembling mechanisms ceases. The press ram stops at the end of a stroke already started.

If solenoid SOL1 (Fig. 77) is energized, in a manner to be described, by absence or improper location of a condenser part, switch 601 of PB1 is automatically opened but the motors M2 and M3 do not stop immediately. Switch 601 is shunted by switch SW5 which, as shown in Fig. 12, has an arm 670 carrying a roller 671 engageable with the periphery of the dial M. As the dial M approaches a stopping position, roller 671 is spring urged into a notch 513 of the dial and opens switch SW5 so that coils 640 and 650 are deenergized. Motor M2 is disconnected from the current source but coasts long enough to cause the notch 513 of dial M to rotate slightly past the position in which the notch 513 received the roller 671. Thus the switch SW5 is opened momentarily as dial M approaches a stopping position and then closes again when the dial coasts to its stopping position. Before switch SW5 closes again, switches PR1 and PR2 have opened. Closing of switch SW5 again at the stopping position of the dial has no effect except 35 switch SW5 is reset for a subsequent function.

Therefore the energization of solenoid SOL1 causes the machine to stop with the dial M at the end of its index. If cam shaft 22 were running at the time solenoid SOL1 had been energized it would continue to run to cause retraction of the feeding plungers and to cause the conveyor B to start and the conveyor would be indexed for one cycle and would stop when dial M stops. Thus the absence or improper location 40 of a condenser part causes the machine to stop at the end of the cycle.

A transformer TR1 (Fig. 77) has a primary connected with wires 641 and 642 and a secondary connected with wires 680 and 681, respectively, by a manually reset, thermal overload switch SW6. Wire 681 is connected with wire 681a through the contacts 682 of relay R5 whose coil 683 is connected with motor M3 so that contacts 682 are closed while motor M3 is running. 55

The checker switches SW8, SW9, SW10, SW11 and SW12 are connected with wire 681a and with the coils 685, 686, 687 and 688 of their associated relays R1, R2, R3 and R4 as shown in Fig. 77. Both the switches SW11 and SW12 are associated 60 with relay R4. These relays are connected with wire 689 connected by switch SW13 with wire 680. Relays R1, R2, R3 and R4, when energized, effect the closing of contacts 691, 692, 693 and 694, respectively. Either of the relays, when energized, causes solenoid Sol1 to be energized, and stop switch 601 is opened. The dial motor M2 stops and the dial stops at the next stopping position. The conveyor B cannot be started and the cycle of the assembling apparatus will not begin until motor M2 can be started again. Motor M2 cannot be started again until the cause for the closing of any of the checker switches has been removed. Lamps l1 (Fig. 41), l2 (Fig. 43), l3 (Fig. 49), l4 (Fig. 70) parallel relay coils 685, 686, 687, 688, respectively, to indicate the ener-

gization of the relays R1, R2, R3, R4, respectively. The operator can tell by the burning of these lamps at which of the feeder stations the trouble has occurred and can remedy the trouble by adding a missing part or properly locating a misplaced part.

When relays R1, R2, R3 and R4 are energized, contacts 691a, 692a, 693a and 694a, respectively, are closed in order to by-pass switches SW8, SW9, SW11, SW12 and SW10, respectively. Therefore, the steady energization of the relays and the steady burning of the indicator lights can be effected regardless of vibrations of the feelers of the checking devices.

When the trouble which caused energization of solenoid SOL1 is remedied, the machine is started again by movement of lever 602 (Fig. 73) to the left to permit switch 601 to close and the switch 600 is momentarily closed. As lever 602 is thus moved, switch SW13 is momentarily opened to deenergize solenoid SOL1 and any of the relays R1 to R4 which had been energized.

Wires 680 and 681a are connected with the primary of a transformer TR2 whose secondary is connected with shaker switch SW7 and the shaker or vibrator 211 (Fig. 53) which shakes the can to cause the washer to descend to the bottom of the can when SW7 is closed by lever 214 (Fig. 53).

While the embodiment of the present invention as herein disclosed, constitutes a preferred form, it is to be understood that other forms might be adopted, all coming within the scope of the claims which follow.

What is claimed is as follows:

1. A machine for assembling an electrical condenser having a metal can, a foil winding having foil margins exposed respectively at its ends, a terminal wire, devices for connecting the foil margins respectively with the can and wire, and a non-conducting can cover through which the wire extends, said machine comprising means for assembling a can, a connecting device and a foil winding, a work holder for receiving first a terminal assembly of the wire, can cover and the other connecting device and then the assembly which is provided by the first means, means for transferring the assembly last mentioned to the work holder and causing the said other connecting device and the can cover to be located within the can, means cooperating with the work holder to crimp the can end against the can cover, means for moving the work holder when loaded to the crimping means and apparatus for effecting operation of said means in timed relation.

2. A machine for assembling an electrical condenser having a metal can, a foil winding having foil margins exposed respectively at its ends, a terminal wire, devices for connecting the foil margins respectively with the can and wire, and a non-conducting can cover through which the wire extends, said machine comprising magazines respectively for holding stacks of cans, connecting devices and foil windings, a conveyor having work holders each for receiving a can into which a device and a winding is to be placed, means for transferring a can from the can magazine to a work holder, means for transferring a device from the device magazine to a can in a work holder, means for transferring a winding from a winding magazine to a location within a can and upon a device therein, a second conveyor having work holders each for receiving first a terminal assembly of the wire, can cover and the other connecting device of the condenser

and then the assembly of can, device and winding, means for transferring the last mentioned assembly from a work holder of the first conveyor to a work holder of the second conveyor whereby the connecting device and the can cover of the terminal assembly are received within the can between the winding and the open end of the can, a press having means cooperating with the work holder to crimp the can end against the can cover, means for causing the operation of the crimping means and movement of the second conveyor alternately in timed relation, and means under control by the second conveyor for causing the operation of the transfer means and the first conveyor alternately in timed relation with respect to the second conveyor whereby the transfer means and the can crimping means of the press operate when the conveyors are at rest and vice versa.

3. In a machine for assembling electrical condensers, the combination comprising a conveyor having work holders each for receiving parts as the work holders move successively to part feeding stations, part feeding apparatus located respectively at said stations, a device for securing together the condenser parts assembled in the conveyor work holders and having an intermittently moving dial carrying work holders, an apparatus for transferring the assembled condenser parts from a conveyor work holder to a dial work holder, a shaft for operating the apparatus, a shaft for operating the conveyor, a driving member and power source connected therewith, automatic-throw-out clutches respectively for connecting the driving member with the conveyor shaft and the apparatus shaft, means under control by the dial for tripping the clutch which connects the drive member with the conveyor shaft and means under control by the conveyor shaft for tripping the clutch which connects the drive member with the apparatus shaft.

4. The combination specified in claim 3 further characterized by the inclusion of apparatuses (operated by said apparatus shaft) for sensing the absence of parts assembled upon the conveyor work holders and means under control thereby for stopping the machine when a part is missing.

5. In a machine for assembling electrical condensers, the combination comprising a chain conveyor, sprockets supported for rotation with their axes horizontal and around which the chain passes to locate the chain in horizontal upper and lower runs, work holders attached to the chain and each adapted to receive a first sub-assembly of condenser parts including a metal can, a metal connector, and a winding of foils and strip insulation, the foils having margins extending respectively beyond the insulation to provide winding terminals, one of the winding terminals resting on the connector received by the bottom of the can, devices which respectively cause said parts of the first sub-assembly to be assembled with the holders, a mechanism which causes movement of the conveyor intermittently to present the holders to the assembling devices and which then causes operation of the assembling devices while the conveyor is stationary, a horizontal dial, work holders supported thereby and each receiving a second sub-assembly including a cover, a second connector upon the cover and a terminal attached to said connector and extending below the cover, means supporting the dial for movement to locate the dial holders so

loaded successively in alignment with a first sub-assembly moved by a work holder of the chain conveyor when the latter work holder is on the lower run of the conveyor and the first sub-assembly is inverted, means for retaining the first sub-assembly in a chain conveyor work holder as the chain passes around a sprocket, means for yieldingly retaining the first sub-assembly in position above a dial work holder positioned to receive it, means operated by said mechanism for transferring the first sub-assembly to said dial work holder and into loose assembly with said second sub-assembly, means provided by the dial work holder to cause, when the can is forced downwardly, the lower edge of the inverted can to be formed against the cover to retain it and to cause said second terminal to be pressed against the foil margin adjacent thereto, and a press to which the dial carries the work holders in succession and which forces the can downwardly.

6. In a machine for assembling electrical condensers the combination comprising first and second conveyors, work holders moved by the first conveyor and each for receiving a first sub-assembly of condenser parts, work holders moved by the second conveyor each for receiving a second sub-assembly of conveyor parts, devices for progressively assembling the parts of the first sub-assembly with the work holders of the first conveyor following intermittent movements of the first conveyor to locate its work holders adjacent to said assembling devices, means for transferring each first sub-assembly into loose assembly with a second sub-assembly on a holder of the second conveyor while stationary, a press to which the second conveyor carries said loose assembly and which operates to secure together the two sub-assemblies, a first mechanism for indexing the first conveyor, a second mechanism for operating the assembling devices and transfer means, a power source, a first clutch for connecting the power source with the said first mechanism, for one cycle of conveyor indexing, a second clutch for connecting the power source with the second mechanism for one cycle of operation thereof, a control member caused by the second conveyor to move into a first position during indexing of the second conveyor and into a second position at the completion of second conveyor indexing, a first clutch tripping apparatus, a link for connecting the first clutch tripping apparatus with the member and actuated by said member when moved from its second to its first position for causing the first clutch to connect the power source with first mechanism, means operated by the first mechanism for disconnecting the link from said member to allow the first clutch to disengage at the end of one first conveyor indexing cycle, means for latching the link disengaging means in disengaged status, means operated by the first mechanism for tripping the second clutch to connect the first source with the second mechanism for one cycle of its operation and means operated by the second mechanism for releasing the latching means to permit return of the latch to position for re-engagement by said member, said re-engagement being effected in response to movement of said member from first to second position at the end of second conveyor indexing.

7. In a condenser assembling machine the combination of first and second conveyors, first and second work holders moved respectively thereby and adapted to support respectively first and sec-

ond condenser sub-assemblies, devices for assembling progressively the parts of the first sub-assembly with the first work holders, a first mechanism for indexing the first conveyor, a second mechanism for operating the assembling devices, a first electric motor for supplying power to operate said mechanisms, a first clutch for connecting the first motor with the first mechanism for one cycle of first conveyor indexing, a second clutch for connecting the first motor with the second mechanism for one cycle of operation thereof, means operated by the second mechanism for transferring the first sub-assembly to a second work holder of the second conveyor, apparatus for uniting the two sub-assemblies while on a second work holder, a second electric motor for indexing the second conveyor and for operating said apparatus, means under control by the second conveyor for tripping the first clutch, means under control by the first mechanism for tripping the second clutch, magnetic switches respectively for connecting the motor with an electric current source, a circuit for maintaining energization of the magnetic switches including contacts of these magnetic switches and including first and second switches in parallel and biased into closing position, means for opening the first of the parallel switches when stopping of the motors is desired and means controlled by the second conveyor for causing the momentary opening of the second of the parallel switches just ahead of the completion of indexing of the second conveyor whereby the magnetic switches operate to disconnect the two motors from the current source and the second motor coasts to complete indexing of the second conveyor and the second parallel switch closes.

8. The combination according to claim 7 further characterized by the provision of means for automatically opening the first parallel switch, said means comprising a spring, a mechanism for transmitting force of said spring to said first parallel switch to open it against its own closing bias and including a link and a lever for transmitting spring actuated link movement to the first parallel switch, a toggle connected with the link and straightened by the lever, when moved away from the first parallel switch, for retaining the link in spring-cocking position, a solenoid having an armature for breaking the toggle when the solenoid is energized, means sensing the absence of a part from the first sub-assembly, means rendered operative by the sensing means for causing the solenoid to be energized when a part is absent, a normally closed switch in the energizing circuit of the solenoid, and means operated by movement of the lever to spring-cocking position for momentarily opening said switch to cause deenergization of the solenoid.

9. For use with a condenser assembling machine having a conveyor, work holders moved thereby and each adapted to receive parts of an assembly, devices for progressively assembling the parts with the work holders, means for operating the assembling devices and means for intermittently moving the conveyor to locate the holders successively adjacent to the assembling devices, the combination comprising a cam operated by said first means, an electric switch, means controlled thereby for causing the machine to stop operating, a mechanism operated by the cam for conditioning the switch for machine stopping in response to absence of a part from a work holder and a mechanism operated by the cam for conditioning the switch for machine stopping in re-

spose to the extension of a part to more than a predetermined distance from the work holder.

10. For use with a condenser assembling machine having a conveyor, work holders moved thereby and each adapted to receive parts of an assembly, devices for progressively assembling the parts with the work holders, means for operating the assembling devices and means for intermittently moving the conveyor to locate the holders successively adjacent to the assembling devices, the combination comprising a cam operated by said first means, an electric switch, means rendered effective by the closing of said switch for causing the machine to stop, a feeler for engaging a part supported by the work holder, a first lever pivotally supported and connected with the feeler, a second lever directly positioned by the cam, an extensible link connecting the levers and comprising members respectively directly connected with the levers and having portions in parallelism, parallel arms connecting the parallel portions, a spring urging the levers toward each other and the parallel portion of the link members toward each other to obtain the minimum length of the link, said cam having a contour such as to cause retraction of the feeler through movement transmitted to the first lever by the second lever and the link in least extended status and such as to permit the spring to impart movement to the first lever greater than that which would cause the feeler to engage a part properly positioned upon the work holder, and a mechanism for controlling said switch and normally in status such that the switch is open and operated from normal position by the first lever if the part with which the feeler is adapted to engage, is not present upon the work holder and operated from normal position by pivotal movement of one of said arms if movement of the first lever toward the work holder is obstructed by engagement of the feeler with a part extending more than a certain distance from the work holder, closure of said switch resulting from movement of said mechanism from normal status.

11. For use with a condenser assembling machine having a conveyor, work holders moved thereby and each adapted to receive parts of an assembly, devices for progressively assembling the parts with the work holders, means for operating the assembling devices and means for intermittently moving the conveyor to locate the holders successively adjacent to the assembling devices, the combination comprising a cam operated by said first means, an electric switch, biased normally closed, a third lever for controlling said switch and spring biased into normal position for opening the switch, means rendered effective by the closing of said switch for causing the machine to stop, a feeler for engaging a part supported by the work holder, a first lever pivotally supported and connected with the feeler, a second lever directly positioned by the cam, an extensible link connecting the levers and comprising members respectively directly connected with the levers and having portions in parallelism, parallel arms connecting the parallel portions, a spring urging the levers toward each other and the parallel portion of the link members toward each other to obtain the minimum length of the link, said cam having a contour such as to cause retraction of the feeler through movement transmitted to the first lever by the second lever and the link in least extended status and such as to permit the spring to impart movement to the first lever greater than that which would cause the

feeler to engage a part properly positioned upon the work holder, said third lever having an arm located in the path of movement of the first lever so as to be moved thereby from normal into switch closing status if the part, with which the feeler is adapted to engage, is not present upon the work holder, said third lever having an arm located in the path of pivotal movement of one of said link arms so that the third lever arm will be moved by said one of the link arms if movement of the first lever toward the work holder is obstructed by engagement of the feeler with a part extending more than a certain distance from the work holder.

12. For use with a condenser assembling machine having a conveyor, work holders moved thereby and each adapted to receive parts of an assembly and a mechanism for intermittently moving the conveyor and for operating a parts feeder having a chute, the combination comprising a horizontal support for receiving a part delivered from the feeder chute and having a hole spaced from the chute and adjacent to a work holder located below it, means operated by the mechanism for transferring the part from position adjacent the chute to position adjacent the hole, means operated by the mechanism for pushing the part from the transfer means, through the hole and upon the work holder and means for maintaining alignment of the part with the work holder after said part leaves the transfer means.

13. For use with a condenser assembling machine having a conveyor, work holders moved thereby and each adapted to receive parts of an assembly and a mechanism for intermittently moving the conveyor and for operating a parts feeder having a chute, the combination comprising a horizontal support for receiving a part delivered from the feeder chute and having a hole spaced from the chute and adjacent to a work holder located below it, a horizontally movable transfer located upon the support and comprising jaws for gripping the part, spring means for urging the jaws into engagement with the part, means connecting one of the jaws with said mechanism for movement of said jaws between position adjacent the chute and position adjacent the hole, a stop for arresting movement of the other of said jaws as the jaws are moved toward the chute to separate the jaws so that the part is received between them, the movement of the jaws away from the chute permitting the spring means to operate to close the jaws upon the part, a plunger operated by the mechanism for moving the part from the jaws, through the hole and into the work holder adjacent thereto and means for maintaining alignment of the part with the work holder as the part leaves the jaws.
